Primary Examiner — Robert M Spear(74) *Attorney, Agent, or Firm* — Blue Filament Law PLLC; Avery N. Goldstein(57) **CLAIM**

The ornamental design for a nozzle, as shown and described.

DESCRIPTION

FIG. 1 is a front view of the nozzle;
FIG. 2 is a left side view of the nozzle depicted in FIG. 1;
FIG. 3 is a right view of the nozzle depicted in FIG. 1;
FIG. 4 is a top view of the nozzle depicted in FIG. 1;
FIG. 5 is a side elevated perspective view of the nozzle depicted in FIG. 1;
FIG. 6 is a top elevated perspective view of the nozzle depicted in FIG. 1;
FIG. 7 is a bottom view of the nozzle depicted in FIG. 1; and,
FIG. 8 is a rear view of the nozzle depicted in FIG. 1.
The broken lines in the drawings represent unclaimed environmental subject matter and form no part of the claim.
